175,992

MANUALLY OPERABLE INDICATOR FOR DISPLAYING VARIABLE INFORMATION

Desmond John Turner, Surbiton, England

Application July 14, 1954, Serial No. 31,419

Term of patent 3½ years

(Cl. D52—1)

FIG. 1.

FIG. 2.

FIG. 3.

FIG. 4.

Fig. 1 is a front perspective view from above and one side of a manually operable indicator for displaying variable information, showing my new design;

Fig. 2 is a rear elevation;

Fig. 3 is a side elevation taken in the direction of arrow A of Fig. 1; and

Fig. 4 is an underneath plan.

I claim:

The ornamental design for a manually operable indicator for displaying variable information, substantially as shown.
